DESIGN FOR A COMBINED KNIFE, PENCIL, AND WATCH

Jack Tamis, New York, N. Y.

Application June 30, 1936, Serial No. 63,579

Term of patent 3½ years

To all whom it may concern:

Be it known that I, Jack Tamis, a citizen of the United States, residing in the city of New York, Borough of Bronx, county of Bronx, and State of New York, have invented a new, original, and ornamental Design for a Combined Knife, Pencil, and Watch, of which the following is a specification, reference being had to the accompanying drawing, forming part thereof.

I claim:

The ornamental design for a combined knife, pencil, and watch, as shown.

JACK TAMIS.
